UNITED STATES PATENT OFFICE.

JOSEPH KEPPLER, OF NEW YORK, N. Y., ASSIGNOR TO BENJAMIN T. B. HYDE, OF NEW YORK, N. Y., TRADING AS HYDE EXPLORING EXPEDITION.

DESIGN FOR A SUPPORT AND LEG FOR FURNITURE.

SPECIFICATION forming part of Design No. 36,236, dated February 24, 1903.

Application filed January 12, 1903. Serial No. 138,771. Term of patent 7 years.

To all whom it may concern:

Be it known that I, JOSEPH KEPPLER, a citizen of the United States, residing at New York, in the county and State of New York, have 5 invented and produced a new, original, and ornamental Design for a Support and Leg for Furniture, of which the following is a specification, reference being had to the accompanying drawing, forming part hereof, and 10 which is a perspective view of a support and leg, showing my new design.

As illustrated in the drawing, the leading or material feature of my design consists of the outline or configuration of the support 15 and leg, in conjunction with the surface ornamentation thereof. The surface of the support and leg is ornamented by the representation of two Katzinias *a* and *b*, each being an Indian god, arranged side by side, one Kat 20 zina having a round head or face *a'*, while the other has a square head or face *b'*. The bodies *a²* and *b²* are elongated and have feet *a³* and *b³*, turned, respectively, opposite to each other.

The arms *a⁴* and *b⁴* support a horizontal head-piece *d*, on which is depicted certain symbols 25 *d'* and *d²*, adjacent to the heads *a'* and *b'* of the Katzinias. In outline the top *d* is rectangular and merges by angular arms *a⁴* and *b⁴* into the rectangular body portions *a²* and *b²*. The body portions *a²* and *b²* terminate in flaring portions *f* and *f'*, surmounting two truncated pyramidal portions *g* and *h*, which in turn surmount the zigzag feet *a³* and *b³*.

Having described my invention, what I claim as new, and desire to secure by Letters 35 Patent, is—

The ornamental design for a support and leg for furniture substantially as herein shown and described.

In testimony whereof I have hereunto set 40 my signature in the presence of two subscribing witnesses.

JOSEPH KEPPLER.
